UNITED STATES PATENT OFFICE.

FRANKLIN CHATFIELD, OF MINNEAPOLIS, MINNESOTA, ASSIGNOR TO NORTHWESTERN KNITTING COMPANY, OF MINNEAPOLIS, MINNESOTA, A CORPORATION.

UNDERGARMENT.

1,308,396.

Specification of Letters Patent. Patented July 1, 1919.

Application filed October 11, 1912. Serial No. 725,203.

To all whom it may concern:

Be it known that I, FRANKLIN CHATFIELD, of Minneapolis, Hennepin county, Minnesota, have invented certain new and useful 5 Improvements in Undergarments, of which the following is a specification.

My invention relates to union undergarments and particularly to that type having a closed crotch, and the object of the invention is to provide a pair of combined gores and flaps for closing the posterior opening of the garment and the crotch and allowing sufficient fullness of the goods for an ample or wide opening.

15 A further object is to provide a garment in which the pull of the flaps in exposing the opening will be on the elastic portion of the fabric, where considerable stretch will be obtained, rather than upon the seams in 20 the crotch or the back of the garment.

A further object is to provide improved means for attaching the under flap to the back of the garment.

The invention consists generally in the 25 garment hereinafter described and particularly pointed out in the claim.

In the accompanying drawings forming part of this specification,

Figure 1 is a rear view of a portion of the 30 garment embodying my invention,

Fig. 2 is a similar view, showing the flaps spread apart to expose the opening,

Fig. 3 is a similar view, showing the under flap in its closed position,

35 Fig. 4 is a detail view of the pair of combined gores and flaps, showing the preferred means of stitching them together,

Fig. 5 is a similar view, showing a slightly modified construction.

40 In the drawing, 2 represents a union-suit garment made of fabric tubing, or knit flat or woven, as preferred, having the usual front opening 3. When the garment is made from a fabric tube, the tube is slit at the 45 back to form the posterior opening and to allow for the insertion of the gores at the thigh portions of the legs. The preferred form of opening I have indicated at 4 in Fig. 2. The gores 5 and 6 are preferably

50 triangular in form, having lower portions 7 which extend down into the legs and are stitched to the inner leg portions. The inner edges of these gores lap by one another, as indicated in Fig. 4, and are stitched to-

gether at 8, some little distance from the 55 point where the lower edges of the gores 7 are stitched to the front of the garment. The position of these stitches 8 causes the pull in separating the flaps to be exerted on the fabric itself, instead of the row of 60 stitches at the lower ends of the gores, consequently there will be greater freedom of movement of the flaps and a wider opening is thereby obtained. The outer side edges of the gores are stitched to the back of the 65 garment on each side of the opening therein and extend upwardly to a point above the waist line and are attached at 9 to the middle portion of the garment. The inner edges of the gores lap by one another and effectively 70 close the posterior opening, and the gore 5 has a button 10 on its inner edge to engage a tab 11 that is secured to the back of the garment on the inside. The outer flap 6 is buttoned at 12 to the back of the garment on 75 the opposite side of the opening and covers the longitudinal seam of the gore 5 and cooperates with this gore to form a double thickness at the back of the garment.

In Fig. 5 a slightly modified construction 80 is shown, in which at 13 the gores are stitched together by parallel rows of stitches instead of diverging rows, as shown in Fig. 4. The result, however, is practically the same, as the pull in separating the flaps will be 85 exerted on the fabric itself instead of on the seam at the lower ends of the gores.

I claim as my invention:—

A bifurcated undergarment, having a permanently closed crotch, formed by a pair of 90 correspondingly shaped seat-piece insertions, each having its lower angle formed into a single thigh-gore extension, seamed to the edge of the front side inseam of the corresponding leg, from the point of said extension upwardly to and beyond the front median line of the garment and lapping by the corresponding portion of the other seat-piece insertion and stitched thereto by a row of stitches extending downwardly at one 95 side of the front median line of the garment, one of the lateral edges of each seat-piece being joined to the edge of the corresponding rear side body and leg portion of the garment, from the point of the thigh-gore 100 extension to a point above the seat, the other lateral edge of said seat-piece left free from the lower end of the front row of stitches,

joining it to the other seat-piece, to a point above the seat, and means for detachably connecting the free edge of each seat-piece at a point substantially mid-way of its 5 length to the body of the garment beyond the line of permanent attachment of the other seat-piece, substantially as described.

In witness whereof I have hereunto set my hand this 3d day of October, 1912.

FRANKLIN CHATFIELD.
